UNITED STATES PATENT OFFICE.

WILL FRANCIS BENNETT, OF LOGANSPORT, INDIANA.

GATE.

SPECIFICATION forming part of Letters Patent No. 438,050, dated October 7, 1890.

Application filed June 19, 1889. Renewed August 7, 1890. Serial No. 361,356. (No model.)

To all whom it may concern:

Be it known that I, WILL FRANCIS BENNETT, a citizen of the United States, and a resident of Logansport, in the county of Cass and State of Indiana, have invented certain new and useful Improvements in Gates; and I do hereby declare that the following is a full, clear, and exact description of the invention, which will enable others skilled in the art to which it appertains to make and use the same.

My invention relates to improvements in that class of farm-gates or other gates that, in addition to being opened and closed by pedestrians, may be opened and closed by approaching and receding vehicles; and it consists in the construction and novel combination of parts, as will be hereinafter fully described and claimed.

Figure 1 of the drawings is a view in perspective of the improved guiding-block to be used in connection with a gate that is designed to be opened automatically. Fig. 2 is a view of a gate provided with the improved block and the ordinary operating crank-rods and lever, by which the gate is swung to and fro on its hinges; and Fig. 3 is a detail view of one of the operating-levers.

Referring by letter to the accompanying drawings, A designates the hinge-post, and C D the pintles in the hinge-post, upon which the gate is hung to swing open and shut.

E and F are double-crank rods, supported in suitable bearings so that they may be operated by the wheels of passing vehicles.

G and H are levers connected to the crank-rods and having catches I to detain the gate till the wagon has passed. The novelty in this instance consists in the guide-block M, secured to the hinge-post by a bolt and nut or in any other suitable manner. This guide-block comprises a head portion N, having two nearly V-shaped projections P Q, with their forward enlarged ends separated by a vertical passage or groove R, the lower end of which communicates with the cam-shaped groove R', which is arranged at substantially a right angle to the projections and the vertical groove and is beneath the under face of the projections.

The gate is provided with a pin S, having a friction-roller T, which is adapted to travel in the head-block when the gate is opened and closed, as will presently appear.

This being the construction, the operation

is as follows: When the gate is closed, the friction-roller T is immediately below and in line with the vertical groove R of the head-block and the inner ends of the levers are under the hinge-post of the gate. When it is desired to open the gate, one of the levers is depressed at the outer end, which elevates the inner end, causing the same to lift the gate and move the friction-roller up the groove R to clear the same, when it will travel down the upper face of one of the projections, consequently opening the gate, and the catch I on the lever will, when the gate is opened, retain the same. To close the gate, it is merely necessary to release the catch, when the friction-roller will travel back in the groove R' and assume its normal position, thus closing the gate, as will be readily understood from the foregoing description and drawings.

Having thus fully described my invention, what I claim as new, and desire to secure by Letters Patent, is—

1. In a gate, the combination, with the head-block having the projections and the vertical and cam grooves, of the gate having the pin carrying the roller arranged in the cam-groove and under the vertical groove, and the levers having their inner ends arranged under the hinge-bar of the gate, whereby when said inner ends are elevated the gate is caused to open, substantially as described.

2. In a gate, the combination of the pivot-ed levers, the latches carried by said levers, the gate having its hinge-bar above the inner end of the levers, the pin carried by the gate, and the head-block having the vertical and cam grooves arranged and adapted to serve substantially as described.

3. The combination of the gate carrying the pin, the head-block having the vertical groove and the cam-groove, the levers for elevating the gate, and the latches on the levers for retaining the gate, substantially as described.

In testimony that I claim the foregoing as my own I have hereunto affixed my signature in presence of two witnesses.

WILL FRANCIS BENNETT.
